UNITED STATES PATENT OFFICE

125,645

DESIGN FOR A CASING FOR ELECTRIC FENCE CONTROL UNIT

Ralph R. Smith, Lakewood, Ohio, assignor to National Carbon Company, Inc., a corporation of New York

Application July 9, 1940, Serial No. 93,515

Term of patent 14 years

To all whom it may concern:

Be it known that I, Ralph R. Smith, a citizen of the United States, residing at Lakewood, in the county of Cuyahoga and State of Ohio, have invented a new, original, and ornamental Design for an Electric Fence Control Unit, of which the following is a specification, reference being had to the accompanying drawing, forming a part thereof.

Fig. 1 is a front perspective view of an electric fence control unit showing my new design;

Fig. 2 is a top plan view; and,

Fig. 3 is a side elevational view thereof.

I claim:

The ornamental design for an electric fence control unit, substantially as shown.

RALPH R. SMITH.
